(57) **CLAIM**

The ornamental design for a fan lamp, as shown and described.

DESCRIPTION

FIG. 1 is a front and bottom perspective view of a fan lamp showing my new design;

FIG. 2 is a rear and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof, illustrated in a second position; and,

FIG. 10 is an enlarged view of detail 10 encircled in FIG. 1. The broken lines in the figures illustrate portions of the fan lamp that form no part of the claimed design.
